(57) **CLAIM**

The ornamental design for a revolver cylinder cup, as shown and described.

DESCRIPTION

FIG. 1 is a top perspective view of a revolver cylinder cup, showing our new design;

FIG. 2 is a bottom perspective view thereof;

FIG. 3 is a front elevational view thereof, the rear elevational view being a mirror image thereof;

FIG. 4 is a left-side elevational view thereof, the right-side elevational view being a mirror image thereof;

FIG. 5 is a top plan view thereof;

FIG. 6 is a bottom plan view thereof;

FIG. 7 is a cross-sectional view thereof, taken along line 7-7 of FIG. 5; and,

FIG. 8 is a cross-sectional view thereof, taken along line 8-8 of FIG. 5.
